UNITED STATES PATENT OFFICE.

EDWIN EARL BARNARD, OF ILLION, NEW YORK, ASSIGNOR TO MICHIGAN TYPEWRITER COMPANY, OF ILLION, NEW YORK, A SUBSIDIARY OF NEW YORK

TYPEWRITING AND RELATED

1,115,463.

Specification of Letters Patented, November 3, 1914.

Application filed July 10, 1912. Serial No. 2,000.

To all whom it may concern:

Be it known that I, Edwin E. Barnard, a citizen of the United States, and resident of Illion, in the county of Herkimer and State of New York, have invented certain new and useful Improvements in Type-Writing Machines, of which the following is a specification.

My invention relates to typewriting machines and more particularly to the case-shift mechanism of such machines.

My invention has for its principal object to provide improved means for controlling the shiftable element of a typewriter having a so-called double shift; that is to say, one in which the shiftable part has three printing positions, as for example, when in a type bar machine each type bar carries three types.

20 To the above and other ends my invention consists in certain features of construction, and combinations and arrangements of parts, all of which will be fully set forth herein and particularly pointed out in the claims.

In the accompanying drawings there is shown enough of a front strike typewriting machine to illustrate the embodiment of my invention therein.

30 In said drawings, Figure 1 is a front to rear vertical sectional view. Figs. 2 and 3 are front views of two parts of a certain locking lever. Fig. 4 is a front elevation, partly in transverse vertical section. Fig. 5 is a view similar to parts of Fig. 1 but showing one of the shift keys depressed. Fig. 6 is a similar view but showing the other shift key depressed. Fig. 7 is an enlarged perspective view of certain stop devices.

40 The main frame of the machine to which my invention is here shown applied, comprises side pieces, each of which includes a sort of base bar piece 1, two corner posts 2 and an irregularly shaped bar 3 connecting said corner posts at the top. The base bars 1 are connected by a front transverse bar or plate 4 and a rear transverse bar or plate 5. The side pieces are also connected at their top parts by a rear top plate 6 and a forward top plate 7, the latter formed with a sort of well through which the front strike type bars move upward to the platen 8. Said platen is a cylinder mounted in a paper carriage which is not here shown as an illustration of my invention.

50 The type bars 10 each carry three types 11 and said type bars are pivoted at 12 in a side bar segment 13, which segment has forward extending a series of slots radiating 60 from the pivoting point on the front face of said segment 13 from a point near said pivoting point. Only one of these slots is indicated in Fig. 1; namely, the one in which the single type bar shown is mounted. The 65 segment 13 is pivoted a type rest 14 by means of rods 15. Said segment 13 is shiftable to various places printing positions. To this end said segment forms part of a frame, which frame comprises two side bars 16 each 70 pivoted at 17 in a bracket 18 (Fig. 4) projecting toward from one of the rear corner posts 2, said pivot 17 being horizontally in the rear of the pivoting line on the front face of the platen. In the rear of the segment 13, 75 the two side bars 16 are connected by means of a transverse bar 20, the rear face of which is formed with a series of radial slots in which a series of sub-bars 21 are pivoted on a pivot wire 22. Said sub-bars are connected with the type bars in means of links 23. Each of the sub-bars 21 has a rearwardly extending arm to which is connected the upper end of a push link 24, the lower end of which is connected to the rear end of 80 a key lever 25 of the first order. The series of key levers 25 have printing keys 26 on their forward ends, said keys being arranged in three rows and the key levers 25 are accordingly pivoted on three pivot wires 27, 85 one lying in front of another and all secured to the underside of a cross bar 28 which at its ends is fastened to the base bars 1 of the main frame plates. The construction is such that when one of the keys 26 is depressed, 90 the corresponding link 24 is pushed upward and the corresponding type bar 10 is actuated through the sub-bar 21 and link 23. When the segment 13 stands in its middle position shown in Fig. 1 the links 24 have 95 their longitudinal axes passing substantially through the axis of the pivots 17 so that when the segment is shifted up or down the upper end of each of the links 24 moves substantially horizontally front or back and the 100 proper relationship between the key levers and the type bars is not disturbed by the shifting.

The type action and shiftable segment above described, are not of my invention but are the invention of Arthur W. Smith. My invention resides more especially in the mechanism used for shifting the segment 13 and in this sense my invention is in the nature of an improvement on the invention of the said Arthur W. Smith. In another sense my invention may be said to include an improved means for shifting the shiftable part of any typewriter where there are three case shift positions, whether said shiftable part consists of a type bar segment as in the present instance or of a shiftable platen or of some other part of the machine.

In order partially or wholly to counterbalance the weight of the shiftable frame, said frame has mounted thereon and depending therefrom below the pivots 17, an arm 30 to the lower end of which is fastened the rear end of a contractile spring 31, the forward end of which is secured by means including a screw 32 (Figs. 4 and 6) to a lug 33 projecting upward from the cross bar 28. The screw 32 is threaded into a nut which in turn is threaded into the coils of the spring 31 so that the tension on said spring can be varied by turning said screw.

My improved shifting means includes two operating devices, preferably toggles, which when in normal position hold the shiftable part, in this case the segment, in one position and when one of said devices is actuated it moves the shiftable part to its second position and when the other of said devices is actuated it moves the shiftable part to the third position. Preferably both of said operating devices are continuously connected with the shiftable part, and when one of said operating devices is actuated the other of said devices acts as a fulcrum on or against which the actuated device works, and in the present instance this action is brought about by means of a lever connected at different points to both operating devices in such a way that when one of said devices is actuated the other acts as a fulcrum for said lever. The mechanism is capable of a number of modifications and variations in detail so that the particular instance shown in the drawings is to be taken as illustrative merely and the invention is not confined to that particular form.

In the machine shown in said drawings I have secured to the left-hand side bar 16 of the shiftable frame, a sheet metal arm 34, offset as shown in Fig. 4 by a sort of double bend, and at its rear end secured by two screws 35 to the shifting frame. Near its forward end this arm has threaded therein a pivot screw 36 on which is pivoted the hub of the lever 37 above referred to. In the present instance this is a lever of the first order and the two arms thereof are of

equal length and the two operating devices are connected to said lever one to each end thereof. One of said operating devices consists of a toggle having a link 38 pivoted at 39 to the forward end of the lever 37, and a link 40 anchored to a fixed point. In the present instance this link 40 is pivoted on a pivot screw 41 threaded into a post 42, Fig. 4, projecting inward from the frame bar 3. The two links 38 and 40 are connected together by means of a pivot screw 43 passing through one of said links and threaded into the other and preferably provided with a lock nut. Around said screw there is coiled a spring 44, the two ends of which are hooked in under the two links, the tension of this spring being exerted to resist breaking of the toggle toward the rear. The motion of the parts under the impulse of said spring is limited by an ear 45 bent off from a prolongation of the link 38 and said ear, when the toggle is straight, resting against the rear edge of the link 40. When this toggle is straight, it is positively prevented from breaking toward the front and the spring 44 resists any tendency to break it toward the rear. The toggle can, however, be broken toward the rear as shown in Fig. 6 by means of a shift key 46 mounted on the forward end of a shift key lever 47 which is pivoted to the base bar 1 on a pivot screw 48. Forward of said pivot screw the lever 47 is connected by a link 50 with a forwardly projecting arm 51 of the toggle link 40, which link 40 is therefore one arm of a lever. It will be seen that the toggle 38-40 extends from the lever 37 upward and toward the front. The other operating device consists of a toggle extending downward and toward the rear and comprising a link 52 pivoted at 53 to the rear end of the lever 37, and at 54 to the upper end of a companion toggle link 55, which link is pivoted at a convenient point in the base of the machine. In the present instance this link is shown pivoted on the same screw 48 as the shift lever 47. The toggle 52-55 is acted on by a spring 56 tending to break it toward the front of the machine and such breaking of the toggle is prevented by an ear 57 bent off from the prolongation of the link 52 and engaging the rear edge of the link 55. This second toggle is operated by means of a shift key 58 mounted on the forward end of a key lever 60 that lies by the side of the shift key lever 47 but is not pivoted on the screw 48. The lever 60 is a lever of the first order pivoted at 61 on a screw threaded into a suitable lug of the base bar 1 and at its rear end 125 said key lever is formed with an elongated slot 62 into which a pin 63 projects from a lever arm 64 integral with the link 55. The construction is such that when the key 58 is depressed, as shown in Fig. 5, the toggle 130

52—55 is broken toward the rear, thus pulling downward on the rear end of the lever 37. In this operation said lever takes a fulcrum on the pivot 39 at the free end of the 5 toggle 38—40. The lever 37 then acts as a lever of the second order, pulling down the pivot screw 36 and with it the shift frame to its lowermost position shown in Fig. 5 so as to print from the uppermost one of the 10 three types 11. When both toggles are straight, as shown in Fig. 1, the segment occupies its middle position so as to print from the middle one of said three types and in the present embodiment of the invention 15 this middle position is the normal position. When the key 46 is depressed, as shown in Fig. 6, and the upper toggle 38—40 is broken, the lower toggle remaining straight, then the forward end of the lever 20 37 is pulled upward, carrying with it the screw 36 of the shift frame, said lever 37 at this time taking a fulcrum on the point 53 at the free end of the lower toggle. The parts are now in position to print from the 25 lowermost one of the three types 11, as shown in Fig. 6.

It will be perceived that some other form of actuating device than a toggle could be connected one to each end of the lever 37 30 with a result similar in many respects to that of the mechanism herein shown. It will also be observed that in the present instance the two toggles extend in approximately opposite directions and move the segment in opposite directions from a normal middle position, but said toggles can be otherwise arranged with other results.

It is of course desirable when one of the toggles is actuated that the free end of the other shall have either no motion at all imparted to it or else that its motion shall be not of a sufficient extent appreciably to disturb the other shift key. The condition that the free end of the unactuated toggle be disturbed as little as possible, would be fulfilled if the line through the pivots 39 and 53 passed normally a little above the axis of the pivots 17 and if when one of the shift keys was operated said line then passed 45 correspondingly below said axis. In the present instance the line 39—53 in Fig. 1 passes a little below the axis of the pivots 17 and when the parts are in either of their two shifted positions shown in Figs. 5 and 6, this line passes still farther below said axis. The result is an appreciable motion of the free end of the unactuated toggle, but this motion is comparatively slight and is of 50 no practical consequence in the machine.

It will be noted that in the first part of the actuation of either one of the shift keys the shifting of the segment being performed by the breaking of a toggle, the key has a 55 powerful leverage on said segment, which leverage diminishes continuously through

out the stroke of the key. In the particular lay-out shown in the drawings the leverage does not get so low, however, as to make the last part of the stroke too hard.

The middle position of the segment is determined accurately by the two straightened toggles. In order to determine the two extreme positions with like precision, stop devices are preferably employed. The forward end of the plate or arm 34 is formed 70 with a depending sector 65, the forward face of which has its center in the axis of the pivots 17. At the two ends of this sector there project forward stop lugs 66 and 67 adapted to coöperate with two stop devices 75 80 68 and 70, best shown in Fig. 7, which is a perspective view taken from the left-hand side of the machine and looking toward the front of the machine. It will be perceived that the stops 66 and 67 swing up and down 85 at an inclination of somewhere near 45 degrees and the stop bars 68 and 70 are set at a corresponding inclination, and each of them consists of a short bar having an elongated slot 71 therein through which projects 90 a headed screw 72 threaded into a lug 73 projecting upward from near the left-hand end of the cross bar 28. The rear face of the lug 73 is inclined, as shown in Fig. 7, and is formed with a slot, just about wide 95 enough to accommodate the two bars 68—70, which bars lie in said slot back to back as shown. The bar 68 has a beveled stop surface 74 on its upper edge and the bar 70 has a beveled stop surface 75 on its lower edge, 100 the first of these being arranged to coöperate with the stop 66 and the other with the stop 67. It will be perceived that the point at which one of these stops will arrest the segment can be regulated by moving the 105 corresponding bar 68 or 70 in a direction transverse to that of the motion of the stops 66 and 67; that is to say, in the present instance, in a right and left direction. If one of the bars 68 or 70 be adjusted inward it 110 will cause it to arrest the segment sooner and if said bar be adjusted outward it will cause it to allow a little more motion to the segment. The bars are secured in adjusted 115 position by tightening the screws 72.

An interlock is preferably provided between the key levers 60 and 47 as it will be seen that the operation of these devices would not result in a correct action if both keys were actuated at the same time. For 120 most of the purposes of my invention this interlock may be of any suitable character. In its preferred form it comprises a lug 76 depending from the key lever 47 below the pivot screw 61 and an ear 77 bent off from a depending arm 78 of the key lever 60. The parts normally stand as shown in Fig. 1. If the key 58 be depressed the ear 77 moves in under the lug 76 so that operation of the key 43 is prevented as long as the key 130

58 is in depressed position. If the key 46 be operated the lug 76 moves down in front of the ear 77 and prevents operation of the key 58 until the key 46 shall have been restored to normal position.

I have provided a simple shift lock adapted to lock down either one of the keys 58 and 46. To this end each of the key levers 60 and 47 has where said lever passes through the comb plate 79, an arm depending therefrom with a forwardly projecting lug 80. A locking lever is pivoted to the cross frame bar 81, which bar constitutes the back stop for the key levers of the machine and which also supports said comb plate. Said lever has two toes or lugs 82 and 83 projecting therefrom, one toward the left to coöperate with the lug 80 of the key lever 60 and the other projecting toward the right to coöperate with the lug 80 of the key lever 47. In such a construction as that shown it is desirable that these two toes 82 and 83 be independently adjustable and to this end the lever is of a compound or built-up character comprising one strip of sheet metal 84 having the toe 82 projecting therefrom and another strip of sheet metal 85 having the toe 83 projecting therefrom, and said strips of sheet metal are both formed with elongated slots 86 through which extend headed screws 87 which are threaded into a part 88 consisting in the present instance of a piece of sheet metal bent into U-shape and having a pivot 90 extending therethrough and through ears projecting forward from a suitable bracket 91 secured to the frame of the machine. A spring 92 coiled around the pivot 90 and pressing back on the frame at one end and at the other end pressing forward on the lever, tends to move the lower end of the lever toward the front of the machine to the position shown in Fig. 1 where it is arrested by the upper part of the block 88 pressing against the forward face of the bracket 91. One of the plates 84-85 is prolonged upward and has a key 93 bent off therefrom toward the front of the machine. The construction is such that when either one of the shift keys is depressed a depression of the key 93 will rock the lower end of the locking lever toward the rear and one of the toes 82-83, engaging the depressed lug 80, will hold the key in its depressed position as shown in Figs. 5 and 6. The friction between the toe and the lug, due to the force of the restoring spring 44 or 56, is sufficient to overcome the spring 92; but if the depressed key be struck so as momentarily to relieve this frictional pressure, then said spring 92 will restore the locking lever to its normal position and allow the shift key to be restored to its normal position.

65 Various changes can be made in the de-

tails of construction and arrangement without departing from my invention.

What I claim as new and desire to secure by Letters Patent, is:—

1. In a typewriting machine, the combination with a shiftable part having three printing positions, of two toggles, a lever connecting the free ends of said toggles, means for breaking one of said toggles to shift said part to one of said positions, and 75 means for breaking the other of said toggles to shift said part to the other of said positions.

2. In a typewriting machine, the combination with a shiftable part having three printing positions, of two separate toggles which when straight hold said part in one position, means for breaking one of said toggles to move said part to a second position, and means for breaking the other of 85 said toggles to move said part to its third position.

3. In a typewriting machine, the combination with a shiftable part having three printing positions, of two separate toggles 90 which when straight hold said part in one position, means for breaking one of said toggles to move said part to a second position, means for breaking the other of said toggles to move said part to its third position, and stops for arresting said part in those positions to which it is moved by breaking said toggles.

4. In a typewriting machine, the combination with types and a shiftable part having three printing positions, of two separate toggles which when both of them are straight hold said part in a middle position, and means for breaking said toggles to move said part to its extreme positions. 100

5. In a typewriting machine, the combination with types and a shiftable part having three printing positions, of two separate toggles which when both of them are straight hold said part in a middle position, means for breaking said toggles to move said part to its extreme positions, and stops for arresting said part in said extreme positions. 110

6. In a typewriting machine, the combination with types and a shiftable part having three printing positions, of a lever connected to said part, two toggles connected to said lever and acting when straight to hold said part in one of said positions, 115 means for breaking one of said toggles to shift said part to another of said positions, and means for breaking the other toggle to shift said part to its third position.

7. In a typewriting machine, the combination with types and a shiftable part having three printing positions, of two toggles connected with said part, means for breaking said toggles singly to shift said part to different positions, and means whereby one of 125 130

said toggles acts as a fulcrum for the other to work against when the said other toggle is broken.

8. In a typewriting machine, the combination with types and a shiftable part having three printing positions, of a lever connected with said shiftable part, and two operating means one acting on each end of said lever, one of said operating means acting as a fulcrum of said lever when the other of said means is actuated.

9. In a typewriting machine, the combination with types and a shiftable part having three printing positions, of a lever connected with said shiftable part, two operating means one acting on each end of said lever, one of said operating means acting as a fulcrum of said lever when the other of said means is actuated, two keys for actuating said operating means, and an interlock between said keys.

10. In a typewriting machine, the combination with types and a shiftable part having three printing positions, of two case shift key levers side by side but pivoted on different centers, a lug on one of said levers, and an ear on the other of said levers, said lug and ear being so related that when either of said levers is operated said lug and ear block the other of said levers against operation.

11. In a typewriting machine, the combination with two shift keys, of a shift key lock including lugs on said keys, and a locking lever having two abutments for coöperation with said lugs respectively, said lever being built up of two parts, one of said parts having one of said abutments and the other of said parts having the other of said abutments and said two parts being independently adjustable.

12. In a typewriting machine, the combination with two shift keys, of a shift key lock including lugs on said keys, a locking lever having two abutments for coöperation with said lugs respectively, said lever being built up of two parts, one of said parts having one of said abutments and the other of said parts having the other of said abutments and said two parts being independently adjustable, and an interlock between said keys.

13. In a typewriting machine, the combination of two case shift key levers arranged side by side, of a locking lever between said key levers and comprising a compound lever arm, each element of which carries an abutment for coöperation with one of said key levers and the two elements of said compound lever arm being independently adjustable.

14. In a typewriting machine, the combination with types and a shiftable part hav-

ing three printing positions, of two separate toggles which when both of them are straight hold said part in a middle position, means for breaking said toggles to move said part to its extreme positions, two stops spaced wide apart, and coöperating stopping means situated between two stops, said means coöperating with one of said spaced stops to arrest said part in one of its extreme positions, and coöperating with the other of said parts to arrest said stop in the other of its extreme positions.

15. In a typewriting machine, the combination with types and a shiftable part having three printing positions, of two separate toggles which when both of them are straight hold said part in the middle position, means for breaking said toggles to move said part to its extreme positions, two stops movable with said shiftable part and spaced wide apart, and stationary stopping means situated between said spaced stops and coöperating with one of said spaced stops to arrest said part in one of its extreme positions and coöperating with the other of said spaced stops to arrest said part in the other of its extreme positions.

16. In a typewriting machine, the combination with a shiftable type bar segment having three printing positions, of a lever of the first order pivoted to said segment, two toggles extending in opposite directions from the ends of said lever, and shift keys for operating said toggles.

17. In a typewriting machine, the combination with a shiftable type bar segment having three printing positions, of a lever of the first order pivoted to said segment, a toggle extending upward from one end of said lever, a second toggle extending downward from the other end of said lever, shift keys for operating said toggles, and adjustable stopping devices for arresting said segment when one of said toggles is operated.

18. In a typewriting machine, the combination with types and a shiftable part, of two operating toggles, both continuously connected with said part, and means for operating said toggles, the one independently of the other.

19. The combination of a shiftable segment, a lever connected thereto, two toggles, and two operating keys connected thereto, the lever fulcruming on one toggle when one key is operated and fulcruming on the other toggle when the other key is operated.

Signed at Ilion, in the county of Herkimer and State of New York, this 7th day of July A. D. 1913.

EDWIN EARL BARNEY.
